(57) **CLAIM**

The ornamental design for a dispenser, as shown and described.

DESCRIPTION

FIG. 1 is a top, front perspective view showing the new design;

FIG. 2 is a bottom, back perspective view showing the new design;

FIG. 3 is a top plan view showing the new design;

FIG. 4 is a bottom plan view showing the new design;

FIG. 5 is a right side elevation view showing the new design;

FIG. 6 is a left side elevation view showing the new design;

FIG. 7 is a front elevation view showing the new design;

FIG. 8 is a back elevation view showing the new design; and,

FIG. 9 is an exploded top, front perspective view showing the new design.

Within the drawings, the dashed lines show unclaimed portions of the dispenser, and form no part of the claimed design.

1 Claim, 7 Drawing Sheets# US D809,116 S
